SPIRAL CONVEYER

Lloyd G. Burmeister, Milwaukee, Wis., assignor to
 L. Burmeister Co., Milwaukee, Wis., a corpora-
 tion of Wisconsin

Application June 12, 1936, Serial No. 84,868

2 Claims. (Cl. 287—2)

This invention relates in general to improvements in spiral conveyers and more particularly to an improved coupling construction therefor.

Spiral conveyers operating in elongated boxes are commonly employed for transporting grain, such as corn and wheat, and for transporting coal and like products from one part of a mill or factory to another. These conveyers are usually sectional, in which case a predetermined number of the sections are connected by rigid couplings to produce a desired total length. In order to suitably support the sections for rotation in the conveyer box, bearings are suspended at intervals by brackets, usually termed hangers. 10 These conveyers are of substantial length, frequently as long as several hundred feet, and necessarily there are many spiral sections incorporated therein, and many hangers, it being customary to have a hanger at each point of coupling between the sections. In addition, in lengthy conveyers, there is frequently a drive at each end of the conveyer box.

Heretofore, in order to effect a rigid coupling between the sections, the adjacent shaft ends of 25 said sections being tubular, it has been necessary to insert one end of a short coupling member into the tubular end of one of said sections and the other end of the coupling member into the tubular end of the adjacent shaft section, 30 utilizing bolts or the like to lock the telescoping parts to each other. In using these conveyers, it is quite common for portions of the spiral to become stripped or twisted off of the conveyer shaft necessitating repair. Sometimes these 35 repairs can be effected without dismantling the conveyer, but this necessitates shutting down the plant for a substantial length of time, and is therefore an expensive procedure in a busy concern. Very often, the damage to the spiral is so 40 serious as to necessitate replacing one entire spiral section. When this is the case, it is necessary to remove two of the couplings to disconnect the damaged section from the adjacent sections, and with the coupling methods now 45 employed, the coupling members cannot be removed, even after the bolts are taken out, without sliding the adjacent spiral section laterally to free the telescoped end of the coupling member. However, this lateral sliding of the spiral 50 sections is normally prevented by the various hangers and by the drive mechanism at the ends of the conveyer box, so that as a practical matter it is now necessary, when a damaged section is to be removed, to dismantle the end drives and 55 remove all of the hangers throughout the entire

length of the conveyer. Necessarily, when this is done on a 200-foot conveyer, for example, the loss of time is extremely costly.

It is an object of the present invention to provide a sectional spiral conveyer construction 5 wherein the sections are coupled together in such a way that any section can be removed for repair or replacement without in any way disturbing the adjacent sections or hangers.

A further object of the invention is to provide 10 an improved coupling for accomplishing the above result as well as for use in analogous situations.

A more specific object of the invention is to provide a coupling assembly comprising end coupling portions insertable in the tubular ends of 15 adjacent shaft sections to be connected, a center coupling portion positionable between said ends of the adjacent shaft sections, means including cooperating key slots and removable keys for connecting the end coupling portions to the center 20 coupling portion, and readily removable retaining collars for holding the keys in position.

A further object of the invention is to provide 25 a coupling assembly as above described wherein the center coupling portion is journaled in a hanger bearing and projects slightly beyond said bearing on each side thereof, and wherein the end coupling portions project slightly from the ends of the tubular conveyer shaft sections; and wherein there are retaining collars on each 30 side of the bearing to embrace the joints between the projecting coupling portions to hold the keys in position.

A further object of the invention is to provide 35 a coupling construction which is relatively simple, which is inexpensive, which forms a rigid connection between the adjacent shaft ends, and which makes it possible to use unsplit bearings.

With the above and other objects in view, the invention consists of the improved spiral conveyer and all its parts and combinations as set forth in the claims, and all equivalents thereof.

In the accompanying drawing illustrating one complete embodiment of the preferred form of the invention in which the same reference numerals designate the same parts in all of the views,

Fig. 1 is a side elevational view of a conveyer box, parts being broken away and shown in longitudinal section;

Fig. 2 is a longitudinal sectional view through a portion of a conveyer box showing the conveyer and coupling construction therein;

Fig. 3 is a sectional view taken on the line 3—3 of Fig. 2;

Fig. 4 is a detail view in longitudinal section, on an enlarged scale showing the coupling; and Fig. 5 is a sectional view taken on the line 5—5 of Fig. 4.

5 Referring more particularly to the drawing, the numeral 6 designates a conveyer box having therein a spiral conveyer formed of a plurality of connected sections 7, 8, 9, 10, 11 and 12. The connected sections are rotatable in bearings 13 supported by hangers 14. The ends of the conveyer shaft project from the ends of the conveyer box to connect with suitable driving mechanism 15, and 16. The drives 15 and 16 may be 10 motors or the like, or may be gearing suitably 15 driven by a common drive such as overhead pulleys. Material may be conveyed into the conveyer through an inlet 17 to be discharged from an outlet 18 at the opposite end.

It not infrequently happens that foreign material 20 mixed with the material being conveyed, causes damage to the spirals necessitating repair or replacement. Heretofore, due to the type of coupling employed between the shaft sections 7, 25 8, 9, 10, 11 and 12, it was necessary, in order to remove one of the sections of the spiral conveyer, to slide the adjacent sections laterally. Obviously, the drives 15 and 16 as well as the hangers 14 prevent such lateral sliding movement. It has therefore been necessary heretofore to partially 30 dismantle the drives 15 and 16 and remove all of the hangers 14. The present invention relates more particularly to a coupling construction which obviates the above.

35 Referring more particularly to Fig. 4, which shows adjacent reamed tubular ends 19 and 20 of spiral conveyer sections, it will be seen that the coupling assembly comprises end coupling portions 21 and 22 and a center coupling portion 23. The end coupling portion 21 is telescoped within 40 the reamed end portion of the shaft 19 as illustrated with its end 22 projecting slightly beyond the end of the spiral section. A reenforcing sleeve 23 fits over the exterior of the shaft 19, and bolts 24 extending at right angles to each 45 other through cooperating apertures in the sleeve 23, shaft 19 and coupling portion 21, lock the parts together. The other end coupling portion 22 is similarly connected within the shaft 20 by 50 means of bolts 25 passing through cooperating apertures in an external sleeve 26 in the shaft 20 and in the coupling portion 22. The end of the coupling portion 22 also projects slightly beyond the end of the shaft 20 as at 27.

55 The projecting ends 22 and 27 of the coupling portions 21 and 22 respectively are formed with crossing dovetail slots or key-ways 28 and 29. The center coupling portion 23 is formed with cooperating dovetail slots 30 and 31. Keys, of 60 double dovetail form, are insertable in the cooperating slots as shown in Figs. 4 and 5 to rigidly lock the end coupling portions 21 and 22 to the center coupling portion 23. Preferably, each key assembly includes one long key 32 and two 65 short keys 33.

It is to be noted that the center coupling portion 23 is journaled in the bearing 13 of one of the hangers 14, the coupling member projecting from each side of the bearing as at 34 and 35. 70 It is further to be noted that the key-ways or slots of the center coupling portion are formed entirely in the projecting portions 34 and 35 and that the key-ways or slots of the coupling portions 21 and 22 are formed entirely in the 75 projecting ends 22 and 27.

A removable collar 36 is adapted to embrace the line of juncture 37 between the projecting ends 22 and 35. A similar collar 38 is adapted to embrace the line of juncture 39 between the projecting portions 27 and 34. Thus the collars serve to hold the keys in position and prevent the same from falling out of the key-ways or slots.

By referring to Fig. 5 it may be seen that the collars which are identical in construction can 10 be removed by loosening a screw 40 to permit swinging of the two parts of the collar on a hinge pin 41.

It is apparent that with the present construction, if it is desired for example to uncouple the 15 shaft end 19, it is merely necessary to remove a cover part from the conveyer box, remove the collar 36, and remove the keys 32 and 33. If the corresponding collar at the other end of the shaft 19 is similarly removed as well as the keys 20 retained thereby, the entire shaft or spiral section may be lifted completely out of the conveyer box without in any way disturbing the other conveyer sections or any of the hangers. Due to the fact that this procedure can be so readily accomplished, a replacement section can be immediately inserted, and the damaged section repaired 25 at any time that it is convenient. Thus, there is very little lost time necessitated.

With coupling constructions heretofore employed, it was necessary to have the bearing parts 30 13 of split construction so that the lower half of each bearing was removable. With the present invention, however, due to the fact that it is unnecessary to remove the hangers, the bearing 35 portions 13 can be of continuous unsplit form. With the split construction, it is necessary to have holding means in the form of a U-shaped rod for the lower half of the bearing. This rod may now be eliminated so that the hangers form 40 a minimum of obstruction to material carried through the conveyer box.

While this coupling construction is particularly adapted for use in connection with sectional spiral conveyers, this being claimed as a new 45 combination, it is also apparent that the coupling is adapted for other analogous uses. In addition, various changes and modifications may be made in the coupling construction without departing from the spirit of the invention, and all of such 50 changes are contemplated as may come within the scope of the claims.

What I claim is:

1. A separable coupling for use in connection with a support having a bearing, comprising a 55 coupling member adapted to be journaled in said bearing and to have an end projecting a short distance therefrom, a second coupling member having an end abutting the projecting end of the first coupling member, removable 60 means positionable adjacent the bearing for effecting a driving connection between said abutting ends, and a plural part collar embracing said ends and said driving connection and having one end positionable adjacent the bearing, said 65 collar parts being readily removable to provide for disconnecting the coupling without removal of the bearing.

2. A coupling for use in a spiral conveyer having a tubular shaft end and having a supporting 70 bearing comprising a coupling member insertable in said tubular end and having an end adapted to project therefrom, a second coupling member adapted to be journaled in said bearing and to have an end projecting from the bearing and 75

abutting the projecting end of the first coupling member, removable means positionable between the bearing and the tubular shaft end for effecting a driving connection between said abutting ends, and a plural part collar embracing said ends and said driving connection, one end of said collar being positionable adjacent the bearing,

and the other end of said collar being positionable adjacent the tubular shaft end, said collar parts being readily removable to provide for removal of the conveyer shaft without end-wise movement and without removal of the bearing. 5
